CLAIM

We claim the ornamental design for a handheld lancing device, as shown and described.

DESCRIPTION

FIG. 1 is one perspective view of the handheld lancing device, as seen with a lancet projecting from one end;

FIG. 2 is another perspective of handheld lancing device as seen with the lancet end facing away;

FIG. 3 is a front elevational view thereof;

FIG. 4 is a rear elevational view thereof;

FIG. 5 is a top plan view thereof;

FIG. 6 is a bottom plan view thereof;

FIG. 7 is a side elevational view thereof; and,

FIG. 8 is another side elevational view thereof.
